MICROWAVE OVEN CONTROL PANEL

Arthur Franklin Ludvigsen, Burnsville, Minn., assignor to
Litton Systems, Inc., Beverly Hills, Calif.

Filed Mar. 1, 1973, Ser. No. 337,018

Term of patent 14 years

Int. Cl. D7—02

U.S. Cl. D7—135

FIG. 1

FIG. 2

FIG. 1 is a front perspective view of a microwave oven control panel showing my new design; and

FIG. 2 is a front elevational view thereof on a reduced scale with the outline of the front face of the microwave oven shown in broken lines for illustrative purposes only.

The indicia and other details on the face of the dial and the indicia on the lower portion of the panel in FIG. 1 have been omitted from FIG. 2 due to its small scale disclosure.

I claim:

The ornamental design for a microwave oven control panel, as shown and described.
